UNITED STATES PATENT OFFICE.

EDGAR A. TINSMAN, OF WILLOUGHBY, OHIO, ASSIGNOR TO WILLIAM C. OWEN, OF CLEVELAND, OHIO.

DESIGN FOR A TIRE.

55,728.

Specification for Design.

Patented July 6, 1920.

Application filed April 26, 1920. Serial No. 376,881. Term of patent 14 years.

To all whom it may concern:

Be it known that I, EDGAR A. TINSMAN, a citizen of the United States, residing at Willoughby, in the county of Lake and State of Ohio, have invented a new, original, and ornamental Design for Tires, of which the following is a specification, reference being had to the accompanying drawing, forming part thereof.

Figure 1 is a plan view and Fig. 2 a side elevation of a portion of a vehicle tire, showing my new design.

I claim:

The ornamental design for a tire, as shown.

EDGAR A. TINSMAN.
